HEATING CONVECTOR

Edward J. Bair, New Hartford, N. Y., assignor to
Utica Radiator Corporation, Utica, N. Y., a corporation of New York

Application July 26, 1934, Serial No. 737,020

7 Claims. (Cl. 257—150)

The invention relates to space heaters and more particularly to heaters of the so-called convector type. It has for one of its main objects to provide a cast iron heater which will have a very high efficiency so as to compare favorably with the copper heaters now on the market without having any of the disadvantages inherent in heaters made of copper.

Another object is to provide a heater in which the air to be heated is conveyed through a substantial continuous duct which is formed by and made integral with the sections of the heater and which forms part of the secondary heating surfaces. A further object is to so construct the heater sections that they may be connected in various combinations, both vertically and horizontally, and with the inlet and outlet openings at different points, so that they may effectively be built into such spaces or cabinets in which heaters of these types are generally contained.

A still further object is to arrange the customary fins, or secondary heating surfaces, in such a manner that their heat will be given off more effectively. Additional objects are to provide a heater of strong and rugged construction, which will occupy a small space in relation to its heating capacity, which may be assembled and set up with a minimum expenditure of labor, which can readily be adjusted to any height, and which can be manufactured at a comparatively low cost.

These and various other objects and advantages will be readily understood from the following description and from the accompanying drawings of preferred embodiments of the invention in which, however, various modifications may be made without departing from the scope of the appended claims. In the drawings

Fig. 1 is a top view of several sections assembled together and embodying the invention,

Fig. 2 a side view of Fig. 1,

Fig. 3 a top view of a slightly modified heater,

Fig. 4 a longitudinal-sectional side view taken on line 4—4 in Fig. 1,

Fig. 5 another longitudinal-sectional side view taken on line 5—5 in Fig. 1,

Fig. 6 a cross-sectional end view taken on line 6—6 in Fig. 1,

Fig. 7 another cross-sectional end view taken on line 7—7 in Fig. 1, and

Fig. 8 a cross-sectional end view of Fig. 3, taken on line 8—8.

Referring now to all the views simultaneously, the heater consists of a plurality of sections A which may be connected in various combinations,

both vertically and horizontally. Each section contains headers 10 and 11 at opposite ends and in the case of all the views, except Figs. 3 and 8, these headers are connected by two tubes 12 and 13 which are preferably of oval cross-section. A rectangular frame 14, which is spaced from the tubes 12 and 13, extends the whole length of the section and is of substantially the same height as the section.

Each of the sections has an upper and lower port 15 and 16 in its headers, by means of which the sections may be connected together vertically, preferably by means of push nipples. Each nest of vertical sections are clamped together by threaded tie rods 17, which pass through holes 18 drilled in lugs 19 preferably formed between the tubes 12 and 13 and adjacent to the headers. The tie rods are provided with nuts 19.

A plurality of fins 20 extend across the opening between the two tubes 12 and 13 and similar fins 21 extend from these tubes to the frame 14. These fins extend from the center to the top of the section, while a similar set of fins 22 and 23 extends from the center to the bottom of the section. The upper and lower fins on each section are staggered in relation to each other, as plainly shown on Figs. 4 and 5. The sections may also be so assembled that all the fins, throughout the whole vertical nest, are staggered.

Any number of nests of vertical sections may be connected to each other horizontally, preferably by right and left threaded nipples 24 which engage in threads cut in ports 25 and 26 formed in the ends of some of the headers 10 and 11. The inlet pipe is shown at 27 and the outlet pipe at 27A. But it is evident that these pipes, when desirable, may be connected to the ports 26 and 25. All outside ports are threaded and provided with pipe plugs 28. Lugs 29 are formed in the corners of the sections and holes 30 are drilled in these lugs in which legs 31 may be inserted. These legs may be made of any length so as to support the heater any desired height above the surface on which it is placed.

Referring now particularly to Figs. 3 and 8. In this modification only one tube 32 is employed for connecting the headers, otherwise the sections are similar to the ones just described and all the other parts are numbered as in the views just described. A threaded opening 33 is formed in the pipe plug 50 which closes the top of the outlet head. In this hole an air valve may be inserted.

It will be noted that the frames 14 form what is almost a continuous duct through the vertical nests of sections, thus confining the air as it flows 55

upwards through the sections. These frames also form a part of the secondary heating surface, in that they absorb a certain amount of heat from the fins which might otherwise be dissipated, particularly where the heater is installed in a wall recess. Furthermore, the frames support the ends of the fins and prevents breakage.

While I have shown the sections as made up with one or two oval tubes, it is evident that more tubes may be used and that the tubes might be other shapes than oval. It is also evident that the arrangement and staggering of the fins may be varied.

From the foregoing it will be seen that the present heater is of exceptionally strong and rugged construction and may be handled without danger of breakage; that it lends itself to any combination desirable; that it may be installed in any wall space or cabinet; and that the air passing through it is forced into intimate contact with all the heating surfaces, both primary or secondary.

Having described my invention and its objects, which I claim as new and wish to protect by Letters Patent is:

1. A cast metal heater section of the convector type comprising a horizontal tube having a header at each end; a rectangular frame, of substantially the same height as the section, surrounding said tube and said headers; a set of fins formed between the tube and headers and the sides of said frames and extending from the horizontal center axis of the section to the top of the section; another set of fins formed between the tube and headers and the sides of the frames but extending from the center axis to the bottom of the section; said sets of fins staggered in relation to each other; and openings in the top and bottom of said headers for connecting the sections vertically above each other.

2. A cast metal heater section of the convector type comprising a horizontal tube having a header at each end; a rectangular frame, of substantially the same height as the section, surrounding said tube and said headers; a set of fins formed between the tube and headers and

said frames and extending from the horizontal center axis of the section to the top of the section; another set of fins similarly formed between the tubes and between the tubes and the sides of the frames but extending from the center axis to the bottom of the section; said sets of fins staggered in relation to each other; and openings in the top and bottom of said headers for connecting the sections vertically above each other.

4. A cast metal heater section of the convector type comprising a horizontal tube having a header at each end, a rectangular frame surrounding said tubes and said headers, a set of fins formed between the tubes and the headers and the sides of said frames and extending from the horizontal center axis of the section to the top of the section, another set of fins formed between the tube and headers and the side of the frames but extending from the center axis to the bottom of the section, said sets of fins staggered in relation to each other, openings in the top and bottom of said headers for connecting the sections vertically upon each other, and openings in the ends of the headers for connecting the sections horizontally.

5. A cast metal heater section of the convector type comprising a plurality of horizontal tubes having a common header at each end, a rectangular frame surrounding said tubes and said headers, a set of fins formed between the tubes and between the tubes and the sides of said frames and extending from the horizontal center axis of the section to the top of the section, another set of fins similarly formed between the tube and between the tubes and the side of the frames but extending from the center axis to the bottom of the section, said sets of fins staggered in relation to each other, openings in the top and bottom of said headers for connecting the sections vertically upon each other, and openings in the ends of the headers for connecting the sections horizontally.

6. A heater of the convector type consisting of a plurality of cast metal sections, each section comprising a horizontal tube having a header
